JP 6-141940 5/1994

* cited by examiner

Primary Examiner—Stella M Reid*Assistant Examiner*—Mark A Goodwin(74) *Attorney, Agent, or Firm*—Kusner & Jaffe; Michael A. Centanni(57) **CLAIM**

The ornamental design for a cool touch handle, as shown and described.

DESCRIPTION

FIG. 1 is a back perspective view of a cool touch handle showing my new design;

FIG. 2 is a front, perspective view thereof;

FIG. 3 is a back view thereof;

FIG. 4 is a top view thereof;

FIG. 5 is a bottom view thereof;

FIG. 6 is a side view thereof; and,

FIG. 7 is a front view thereof.

The broken line showing of a portion of a washer rack is included for the purpose of illustrating environmental use only and forms no part of the claimed design.
